(57)

CLAIM

The ornamental design for a privacy screen with planter, as shown and described.

DESCRIPTION

FIG. 1 is a front perspective view of a privacy screen with planter, showing the new design;

FIG. 2 is a front elevation view of the privacy screen with planter of FIG. 1;

FIG. 3 is a rear elevation view of the privacy screen with planter of FIG. 1;

FIG. 4 is a bottom plan view of the privacy screen with planter of FIG. 1;

FIG. 5 is a top plan view of the privacy screen with planter of FIG. 1; and,

FIG. 6 is a right side elevation view of the privacy screen with planter of FIG. 1, the left side being a mirror image thereof.

1 Claim, 6 Drawing Sheets(56)
